FIG. 1.

FIG. 2.

FIG. 4.

FIG. 5.

FIG. 6.

FIG. 3.

INVENTOR:
Charles W. Braund

By Bates & Macklin Atty's.

UNITED STATES PATENT OFFICE.

CHARLES W. BRAUND, OF CLEVELAND, OHIO.

WINDOW-SCAFFOLD.

1,325,229.

Specification of Letters Patent.

Patented Dec. 16, 1919.

Application filed April 23, 1918. Serial No. 230,320.

To all whom it may concern:

Be it known that I, CHARLES W. BRAUND, a citizen of the United States, residing at Cleveland, in the county of Cuyahoga and 5 State of Ohio, have invented a certain new and useful Improvement in Window-Scaffolds, of which the following is a full, clear, and exact description, reference being had to the accompanying drawings.

10 This invention relates to window scaffolds and has for its objects the provision of such scaffolds of simple construction, which may be very light and capable of being cheaply manufactured. Another object is to 15 so construct the scaffolds that they may be quickly and securely adjusted to the construction of the window sills and building walls, may maintain an adjustment with security and may avoid injuring the surfaces with which the scaffold contacts.

20 My invention is hereinafter more fully described in connection with the accompanying drawings. Other objects of a more specific nature will become apparent in the 25 description and the essential characteristics thereof are summarized in the claim.

In the drawings, Figure 1 is a side elevation of my scaffold in position; Fig. 2 is an 30 end elevation of the same, looking inwardly toward the wall engaging parts; Fig. 3 is a side elevation of the scaffold removed and folded; Fig. 4 is a detail of the connection between one of the brace members and the bar engaging the outside wall; Fig. 5 is a 35 detail of the joint of the brace arm for the guard rising from the platform; Fig. 6 is a sectional detail showing the device for attaching the chain to the brace arm; Fig. 7 is a cross sectional detail on the line 7—7 40 of Fig. 1.

Describing the invention by the use of reference characters, 1 indicates a platform, formed of one or more boards having their ends fitted into parallel angle irons 3, curved 45 as indicated at 4, one of the flanges of the angle irons being cut free from the other and turned inwardly and secured to a transverse bar 5 adapted to engage the interior of a wall B by a suitable screw or bolt indicated at 2. The bars 3 are made of very 50 light angle iron and are provided on their undersides with longitudinal strips 6, of suitable fibrous material, preferably hard wood. These strips are bolted, riveted or 55 otherwise secured to the horizontal flanges

of the angle bars 3, thus serving to very materially strengthen these bars without adding appreciably to the weight of the device. When in use these strips rest upon the window ledge A, avoiding marring of the ledge. 60 I have found by tests that the angle bars 3 may be strong enough for safety when these bars have substantially only half of the weight that such bars are required to have when the strips 6 are not used. The vertical 65 flanges of such light weight angle bars are sufficiently strong to retain the board or boards constituting the platform securely in position against longitudinal movement, while the strips added to the horizontal 70 flanges have the double function of providing additional strength where most needed and serving as buffers to protect the window sill.

Secured to the vertical flanges of the bars 75 3 by bolts indicated at 10, are brace bars 12, the lower ends of which are bent inwardly and secured by bolts 14 to the transverse bar 15 connecting the ends of the two bars 12 and adapted to engage the exterior of the 80 wall B.

Formed in the bars 12 are a series of openings 16. These openings 16 are adapted to receive a bolt 20, the shank of which may pass through one link of a chain 22 while its 85 threaded end receives a suitable nut, preferably a thumb nut, as shown at 21. A split spring washer 24 is used and a lip turned outwardly sharply as at 25 engages the inner face of the nut, thereby avoiding danger of 90 loosening the nut when the scaffold is in use.

A guard in the nature of a fence is formed around three sides of the platform 1 and is preferably constructed as follows:

Pivots secured by rivets 30 to the upturned flanges of the angles 3, are the ends of a small rod 31 forming an inverted U and extending rearwardly from the pivots a short distance and then upwardly and integrally connected by an intermediate horizontal portion 32. Below the portion 32 is a transverse bar 33 having downwardly turned ends lying along the upright portions 31 and secured by rivets 35. These rivet pins extend outwardly through the bar 31 and 100 through ends of bars 36, substantially parallel with the angle bars 3 and leading to upright bars 38 of substantially the same height as the upright portions 31 and having offset portions at the lower end secured by 105 110

rivets 39 to the bars 3. Above the bars 36 and parallel therewith, are bars 40 pivotally connected at 61 and 62 with the upright bars 31 and 38 respectively. By this construction, it will be seen that I have provided bars parallel with the sides and outer end of the platform 1 and a sufficient distance above the same to form an effective guard for the occupant of the platform.

- 10 To effectually brace the guard structure while permitting it to fold to a position substantially parallel with the platform and closely adjacent thereto, I have provided toggle arms 41 and 42, the arms 41 being 15 pivoted at 63 to the forward ends of the bars 36 by rivets or pivot pins extending through the arms 41 and bars 36 and 38, and also pivoted to the bars 42 by the intermediate pivot pin 45. The arms 42 extend past the 20 pivot pin and overlap the bars 41 and are provided with inwardly turned lips 43, limiting the straightening movement of these toggle arms. The arms 42 are pivoted at 47 to the upright flanges of the bars 3.
- 25 On the bars 5 and 15 are pads adapted to prevent the marring of the inner or outer surfaces of the wall. These pads are indicated at 50 and 52, respectively. It will be seen that they are formed of rubber with 30 normally vertical corrugations made therein, thus effectually preventing lateral shifting of the scaffold when in use.
- The adjustment provided by the bolts 20 and various openings 16 allows the brace bars 12 to assume different angles with relation to the bars 3, thus permitting adjustment of the device for varying thicknesses 35 of the wall B. The result is that once the scaffold is fitted to the walls of the building, 40 it may be used for some time without adjustment, yet where these walls are not uniform, the adjustment may be readily made and when the nuts 21 are once firmly screwed to position, the lip 25 eliminates the danger of

these parts becoming loosened which might 45 result in the fall of the occupant.

Without loosening or changing any of the parts of the structure, it may be folded to the position shown in Fig. 3, it being only necessary to manually move the toggle arms 41 and 42 upwardly out of a straight line, whereupon the fence may be folded toward the platform and obviously the bars 12 will swing readily to the position shown, thus permitting the scaffold to be easily drawn 55 through the window, as well as making it capable of convenient transportation from place to place.

The pads on the bars 5 and 15 are made of considerable thickness and of comparatively 60 short lengths and placed near the ends of the bars, accomplishing the desired results of saving material from which the pads are made, as well as holding the intermediate portion of the bar away from the wall thus 65 providing contact with the wall at separated points whereby unevenness in the wall does not cause an unsteadiness of the scaffold.

Having thus described my invention, what I claim is:—

In a window scaffold comprising a platform and bracing bars, spaced light angle bars supporting the platform, and bent at their inner ends to form hooks of comparatively large curves, strengthening strips of 75 wood rectangular in cross section extending substantially from the outer ends of the angle bars to the curves, and having their inner ends cut away to fit into the curves of the hooks, said strips being secured tightly 80 to the under side of the horizontal flanges of said angle bars whereby they brace and strengthen said bars and act as buffers to protect the window sill.

In testimony whereof, I hereunto affix 85 my signature.

CHARLES W. BRAUND.
